(57) **CLAIM**

We claim the ornamental design for a peg component of a wearable fitness band system, as shown and described.

DESCRIPTION

FIG. 1 is a side view of a peg component of a wearable fitness band system; the opposite side is a mirror image. FIG. 2 is front view of a peg component of a wearable fitness band system; the opposite side is a mirror image.

FIG. 3 is a bottom view of the peg component of FIG. 1. FIG. 4 is a top view of the peg component of FIG. 1; and, FIGS. 5 and 6 are off-angle views of the peg component of FIG. 1.

Stipple shading is used in the accompanying Figures to convey surface contouring, not texture.
